[57] **CLAIM**

The ornamental design for a truck with trailer having hinged sides, as shown and described

DESCRIPTION

FIG. 1 is a right side elevational view of a truck with a trailer having hinged sides embodying my new design.

FIG. 2 is a left side elevational view thereof.

FIG. 3 is a front elevational view thereof.

FIG. 4 is a rear elevational view thereof.

FIG. 5 is a top plan view thereof.

FIG. 6 is a right side elevational view with the hinged sides in an open position.

FIG. 7 is a left side elevational view of the truck as shown in FIG. 6.

FIG. 8 is a front elevational view of the truck as shown in FIG. 6.

FIG. 9 is a rear elevational view of the truck embodiment as shown in FIG. 6.

FIG. 10 is a top plan view of the truck as shown in FIG. 6; and,

FIG. 11 is a perspective view of the truck as shown in FIG. 6.

The bottom plan view is plain and unornamented.
